UNITED STATES PATENT OFFICE.

JOHN B. SYLVESTER, OF BLUE HILL FALLS, MAINE.

SAW-SETTING DEVICE.

SPECIFICATION forming part of Letters Patent No. 352,207, dated November 9, 1886.

Application filed August 3, 1886. Serial No. 209,896. (No model.)

To all whom it may concern:

Be it known that I, JOHN B. SYLVESTER, a citizen of the United States, residing at Blue Hill Falls, in the county of Hancock and State of Maine, have invented a new and useful Improvement in Saw-Sets, of which the following is a specification.

My invention relates to devices for setting the teeth of saws; and the invention consists in certain peculiar and novel features of construction and arrangement, as hereinafter described and claimed.

In order that my invention may be fully understood, I will proceed to describe it with reference to the accompanying drawings, in which—

Figure 1 is a side elevation of my improved saw-set. Fig. 2 illustrates the lower part of the saw-set detached. Fig. 3 is a vertical longitudinal section.

In the said drawings, A and B designate the two members of the saw-set, said members being pivoted together at c and having each a handle, d. Between the handles d is interposed a spring, e, which is secured to one of said handles, and, by pressing on the opposite handle, tends to force them apart. The member A is formed with an oblique slot, a, while the member B is formed with a tongue, b, 30 which extends through and beyond said slot,

and through which passes the pivot c. The member A is further provided with an extension, a', having a flat upper side, and provided at its rear end with a depression, a'', lying contiguous to the shoulder a' of said member. 35 The tongue or set b works in this depression a'', and bends or sets the saw-teeth more or less according as said teeth are inserted to a greater or less extent beneath the set b.

By virtue of the flat form of the upper side 40 of extension a', no twisting of the saw or its teeth can occur. The device is rapid and accurate in operation and convenient to manipulate.

Having thus described my invention, what 45 I claim as new, and desire to secure by Letters Patent, is—

The combination of the member A, having oblique slot a and extension a', with its depression a'', of the member B, having tongue 50 or set b, and the pivot c, substantially as and for the purpose described.

In testimony that I claim the foregoing as my own I have hereto affixed my signature in presence of two witnesses.

JOHN B. SYLVESTER.
